CLAIM

The ornamental design for a display screen with virtual three-dimensional shoe icon or display system with virtual three-dimensional shoe icon as shown and described.

DESCRIPTION

The patent or application file contains a least one drawing executed in color. Copies of this patent or patent application publication with color drawing(s) will be provided by the Office upon request and payment of the necessary fee.

FIG. 1 is a front view of a display screen with virtual three-dimensional shoe icon in which the icon is shown in a perspective orientation;

FIG. 2 is another front view thereof, showing a front orientation thereof;

FIG. 3 is another front view thereof, showing a rear orientation thereof;

FIG. 4 is another front view thereof, showing a side orientation thereof;

FIG. 5 is another front view thereof, showing an opposite side orientation thereof;

FIG. 6 is another front view thereof, showing a top orientation thereof;

FIG. 7 is another front view thereof, showing a bottom orientation thereof;

FIG. 8 is a front view of a display system with virtual three-dimensional shoe icon shown in a perspective orientation, the virtual three-dimensional shoe icon being the same design as shown in FIGS. 1-7;

FIG. 9 is another front view thereof, showing a front orientation thereof;

FIG. 10 is another front view thereof, showing a rear orientation thereof;

FIG. 11 is another front view thereof, showing a side orientation thereof;

FIG. 12 is another front view thereof, showing an opposite side orientation thereof;

FIG. 13 is another front view thereof, showing a top orientation thereof; and,

FIG. 14 is another front view thereof, showing a bottom orientation thereof.

The shoe icon in FIGS. 1-14 is shown in various orientations to provide an understanding of the three-dimensional
